COMBINATION POCKET BURNING AND MAGNIFYING GLASS AND COMPASS

Filed May 31, 1930

INVENTOR.
Herman Neuwirth
Lorus Barnett
ATTORNEY

UNITED STATES PATENT OFFICE

HERMAN NEUWIRTH, OF BROOKLYN, NEW YORK

COMBINATION POCKET BURNING AND MAGNIFYING GLASS, AND COMPASS

Application filed May 31, 1930. Serial No. 457,890.

This invention relates to sportsmen's and boy scouts' accessories and more particularly is directed to an improved construction of a combination pocket burning and magnifying glass and compass.

Among the objects of the invention, is to generally improve the construction of accessories of the character described to provide a device which can be conveniently carried in the pocket, which shall form a rugged structure capable of withstanding hard and rough usage yet shall be neat in appearance, which shall comprise few and simple parts that are readily assembled, and which shall be cheap to manufacture, and practical and efficient to a high degree in use.

Other objects of this invention will in part be obvious and in part hereinafter pointed out.

The invention accordingly consists in the features of construction, combinations of elements and arrangements of parts which will be exemplified in the construction hereinafter described and of which the scope of application will be indicated in the following claims.

In the accompanying drawings, in which is shown one of the various possible illustrative embodiments of this invention:

Fig. 1 is a top plan view of a combination pocket burning magnifying glass and compass constructed to embody the invention, in dot and dash lines the magnifying glass being shown swung out of the housing.

Fig. 2 is a cross-sectional view taken on lines 2-2 in Fig. 1, and

Fig. 3 is a perspective view of the improved one-piece housing.

Referring in detail to the drawings, 10 denotes a device in the form of a sportsman's and boy scout's combination pocket burning and magnifying glass, and compass embodying the invention. Said device 10 is seen to comprise a housing 11 formed of a single flat sheet folded on itself to provide a U-shaped structure having upper and lower portions 11a and 11b, respectively, said portions being positioned in superimposed spaced relation, as shown in Figs. 2 and 3. Said housing may preferably be made of a

resilient metallic stamping having nickel or gilt surface finish. The portions 11a and 11b, are interconnected at one end of the housing by an integrally formed mid-portion 11c, and the free ends of said portions 11a 55 and 11b may be drilled or punched with aligned holes 11d in which a pin 12 is secured.

Said pin serves as a pivoting shaft for a bearing lug 13 extending from a frame 14 which carries a lens or magnifying glass 15, the latter being secured in the frame 14 in any suitable well understood manner. The magnifying glass 15 is preferably circular in shape and the portions 11a and 11b may each be made to have an elliptical contour so 65 as to form a close fitting casing for the magnifying glass and its frame when swung into the housing, as is clearly shown in Figs. 1 and 2.

The mid-portion end of the housing 11 70 preferably terminates in a loop or ring 11e which links with a bail 16, the latter serving to suspend the device 10 from a cord, key ring or chain (not shown) for attaching to a person's wearing apparel.

The upper portion 11a may be formed with a central upwardly extending boss 11f having a perforation or opening 11g, said perforated boss forming a socket in which is securely fitted a compass element 17 of any 80 conventional construction.

The bearing lug 13 is preferably made the same width as the frame 14 or slightly wider than the latter so that normally the frame 14 can be readily swung in and out of the housing. In order to retain the frame 14 in its enclosed position within the housing 11, the lower and upper portions 11a and 11b with the folded mid-portion 11c form a resilient 90 structure for frictionally engaging the frame 14, said portions 11a and 11b providing a spring clamping means, as at X, between the ends of the housing, as shown in Fig. 2.

From the above description, the practical 95 application of the invention will now be apparent. After the parts have been assembled, as shown in Figs. 1 and 2, the device 10 with the frame and magnifying glass positioned, as shown in the full lines in Fig. 1, can be readily carried in the pocket or attached 100

to the chain, cord, or key ring by means of the bail 16, the compass element 17 being available for use in the well understood manner. To use the lens 15 as a magnifying or burning glass, the frame 14 is simply swung out of the housing 11 on the pivoting shaft 12. While the frame 14 is enclosed in the housing 11, the portions 11a and 11b frictionally engage the frame 14 and retain the burning or magnifying glass against accidental swinging movement out of said enclosed position yet give ready access thereto.

It should be noted that should the frame 14 of the magnifying or burning glass become relatively loose on its pivoted bearing due to wear, the spring clamping engagement of the portions 11a and 11b act or may be adjusted to frictionally engage the frame 14 by simply pressing said portions together until they have been set for such frictional engagement.

The provision of the improved one-piece housing 11 formed of a single stamping, as above described, provides a relative inexpensive part which can be cheaply manufactured and readily assembled to the other parts with minimum labor.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. In a device of the character described, a housing formed of a one-piece U-shaped structure, means at the free end of said structure adapted to pivotally support a magnifying glass frame member for swinging movement, the other end of the structure opposite said means being formed with an outwardly extending bail engaging loop, said housing having an integrally formed compass receiving socket between said ends thereof.

2. In a device of the character described, a housing of resilient sheet material having similar shaped portions interconnected by a mid-portion for retaining said shaped portion in superimposed spaced relation, the ends of said portion being adapted to pivotally support a magnifying glass frame member for swinging movement in and out the housing between said shaped portions, said shaped portions adjacent the interconnecting mid-portion formed with spring clamp means

for frictionally engaging said member when swung into the housing.

3. In a device of the character described, a housing comprising a one-piece flat sheet folded over on itself to form springy spaced portions, the free ends of said portion being adapted to pivotally support a magnifying glass frame member for swinging movement in and out of the housing, said spaced portions and fold forming a resilient structure for resiliently clamping said member when swung into the housing.

4. In a device of the character described, a housing comprising a one-piece resilient flat sheet folded over on itself to form springy spaced portions, the free ends of said portions being adapted to pivotally support a magnifying glass frame member for swinging movement in and out of said housing, said spaced portions inwardly of said folded portions of said sheet forming a spring clamp for frictionally engaging said member when swung into the housing, said folded portion of said sheet being looped to provide a bail engaging ring.

5. In a device of the character described, a unitary housing formed of a one-piece flat sheet having similarly shaped portions, a folded mid-portion retaining said shaped portion in superimposed spaced relation, the ends of said shaped portions being adapted to pivotally support a magnifying glass frame member for swinging movement in and out of said housing, said folded mid-portion being looped to provide a bail engaging ring.

6. In a device of the character described, a unitary housing formed of a single flat sheet having similarly shaped portions, a folded mid-portion retaining said shaped portion in superimposed spaced relation, the ends of said shaped portions being adapted to pivotally support a magnifying glass frame member for swinging movement in and out of said housing, said folded mid-portion being looped to provide a bail engaging ring, and a perforated boss outwardly extending from one of said shaped portions forming a compass receiving socket.

7. In a device of the character described, a housing comprising a single flat sheet folded over on itself to form spaced portions, the free ends of said portions being adapted to pivotally support a magnifying glass frame member for swinging movement in and out of said housing, the folded portion of said sheet between said spaced portions being looped to provide a bail engaging ring.

8. In a device of the character described, a housing comprising a single flat sheet folded over on itself to form spaced portions, the free ends of said portions being adapted to pivotally support a magnifying glass frame member for swinging movement in and out of said housing, the folded portion of said sheet between said spaced portions being looped

to provide a bail engaging ring, one of said spaced portions having an integrally formed compass receiving socket.

9. In a device of the character described,
5 a housing formed of a one-piece stamped U-shaped sheet, means at the free end of said sheet for pivotally supporting a magnifying glass frame member for swinging movement, the other end of the housing opposite said
10 means formed with an outwardly extending bail engaging loop.

In testimony whereof I affix my signature.
HERMAN NEUWIRTH.
